A. BRAUNSTEIN

SANITARY NONREFILLING PAPER BOTTLE

Filed May 12, 1922

FIG. 1.

FIG. 2.

FIG. 3.

FIG. 4.

Inventor:
Nov. 13, 1923.
A. Braunstein,
By Mr. G. Dyre,
Atty.

UNITED STATES PATENT OFFICE.

ARON BRAUNSTEIN, OF SAN ANTONIO, TEXAS.

SANITARY NONREFILLING PAPER BOTTLE.

Application filed May 12, 1922. Serial No. 560,477.

To all whom it may concern:

Be it known that I, ARON BRAUNSTEIN, a citizen of the United States, residing at San Antonio, in the county of Bexar and State of Texas, have invented a certain new and useful Improvement of a Sanitary Non-refilling Paper Bottle; and I do hereby declare the following to be a full, clear, and exact description of the invention, such as will enable others skilled in the art to which it appertains to make and use the same.

This invention relates to a certain new and useful improvement of a non-refilling liquid container.

11 The object of the present invention is to produce a non-refilling liquid container made of heavy paper, water-proof treated, being entirely sealed so as to have to break same when liquid is to be removed.

12 Another object of the invention is the production of a sanitary non-refilling bottle made of heavy paper or similar fibrous material having its top corrugated from the surplus material of its lateral walls which seals the upper part of the bottle. The lateral walls are corrugated so as to form the shape and to give its body more strength allowing any rough handling of same.

13 The invention further consists of a production of an economic sanitary non-refilling bottle made of heavy paper which is impregnated in a water proof solution, having a sealing bottom made of sheet metal or other suitable materials lined with a water proof paper, which is affixed to the bottle after filling same, making the bottle air-tight and non-refilling, having to break same to remove contents.

14 In the drawing which shows by way of illustration an embodiment of the invention, Figure 1, is a view of the paper bottle as it is corrugated on top and lateral walls sealed as it will appear in use. Figure 2 is a view of the paper bottle corrugated at the top and lateral walls before sealing and forming the paper bottle; Figure 3 is a longitudinal sectional view of a bottle as in use; Figure 4 is a longitudinal view of a cone made of paper before corrugating same into the bottle shape; Figure 5 is a sectional magnified view of the construction sealing or affixing the bottom to the paper bottle.

15 The present invention comprises a sanitary non-refilling bottle made of a sheet of paper having the top of the bottle sealed

by means of corrugating and over-flapping the paper as shown in Figure 2—line 1.

The lateral walls are corrugated and pressed so as to give it the shape and to make same more substantial.

16 Referring to Figures 1, 2, 3, 4 and 5 of the drawings, the paper bottle consists of a cone made of heavy paper or similar fibrous material having its top sealed by means of corrugating the surplus paper, as shown in Figure 2, line 1, sealing same; also having its lateral walls corrugated as shown in Figure 2, line 2, forming the bottle and to make same more durable, permitting any rough handling of same.

17 The material of which the bottle is made is pliable—yet readily extensible composition, it being preferably formed of paper or other fibrous material.

18 The paper bottle is designated but for single use and its economic value will be correspondingly increased.

19 The bottom is made of sheet metal or other similar material, having an inside lining of water-proof fibrous material. The bottom is fastened to the lower lateral walls of the paper bottle as shown in Figure 2, line 3, after filling same, having to break the bottle at a convenient upper part, in order to remove its contents.

20 The paper bottle is first given a cone shape as shown in Figure 4, after which it is corrugated on top and sides as shown in Figure 1, lines 1 and 2, pressing same so as to seal top and sides forming the bottle.

21 The paper bottle is then impregnated in a sanitary water proof solution which serves to hold together the corrugated parts as shown in Figure 1, lines 1 and 2; Figure 5 shows how the bottom 4 and 5 is fastened to line 3 of Figure 3. In practice, the bottle is filled from the bottom—then sealed by fastening the cover 4 and 5 as shown on drawing—Figure 3 having to break the paper bottle when contents is to be removed.

22 From the foregoing, it would be apparent that I have produced a compact and novel sanitary non-refilling paper bottle which can be produced at a minimum cost.

23 Having thus described my invention, what I claim and desire to secure by Letters Patent is:—

24 1. A sanitary receptacle comprising a tubular member having a lower cylindrical portion and an upper substantially frusto-

2
 5 conical portion, the cylindrical portion having integral longitudinally extending folded flaps, and the small end of the frustro-conical portion being folded substantially perpendicular to the axis of the frustro cone and having integral folded flaps, said flaps being held in folded position by a sealing substance, and said substance sealing the small end of the frustro-conical portion,
 10 10 and a cap arranged on the end of the cylindrical portion to form a complete container, the flaps of the cylindrical portion being of substantially V-shape with the points of the V's arranged adjacent to the base of the
 15 15 conical portion.

2. A sanitary receptacle comprising a tubular member of water-proof fibrous material, the lower portion of the member being of substantially cylindrical shape and
 20 20 having integral V-shaped flaps folded on to one surface of the cylindrical portion, the upper portion of the member being of frustro-conical shape and having its small end folded to form substantially V-shaped flaps
 25 25 lying in a plane substantially perpendicular to the axis of the cylindrical portion, sealing means holding the last mentioned flaps in folded position and sealing the upper end of the member, a cap of relatively stiff
 30 30 material provided with a grooved portion clamped to the lower edge of the cylindrical portion of the member, and a water-proof liner of fibrous material arranged within the cap for maintaining the contents of the
 35 35 receptacle out of contact with said cap.

3. A method of forming a sanitary receptacle consisting in providing a frustro-conical shaped hollow member of fibrous material, forming corrugations at the small end of said member and folding said corrugations over into a plane substantially perpendicular to the axis of the member, placing sealing material on said folded portions to hold the same in folded shape and to seal the small end of the member, also forming 45 V-shaped corrugations at the lower portion of the member and folding these corrugations onto one surface of the member to bring the lower portion of the member into substantially cylindrical shape, and placing 50 a cap on the cylindrical end of said member.

4. A sanitary receptacle comprising a tubular member having a lower cylindrical portion and an upper substantially frustro-conical portion, the frustro-conical portion 55 having a smooth exterior surface and being of substantially uniform thickness throughout, the cylindrical portion having integral longitudinally extending folded flaps of substantially V-shape with the points of the 60 V's arranged adjacent to the base of the frustro-conical portion, and means closing the ends of the tubular member.

In testimony whereof, I affix my signature in presence of two subscribing witnesses.

ARON BRAUNSTEIN.
